UNITED STATES PATENT OFFICE

THOMAS R. COOKSTON, OF ELYRIA, OHIO, ASSIGNOR OF ONE-HALF TO WILBERT G. WISE,
OF AKRON, OHIO

BURIAL VAULT

Application filed October 24, 1929. Serial No. 402,063.

This invention relates to burial vaults.

The general purpose of the invention is to provide a burial vault which will be highly resistant to deterioration and which will not 5 permit the ingress of water thereinto.

More particularly the invention has for its object the provision of a burial vault preferably of a plastic material such as concrete suitably reinforced and having a sheet metal 10 lining preferably of non-corrodible metal such as copper and an improved seal between the bottom and top of the vault to prevent seeping of water therein.

The foregoing and other objects of the invention are attained in the vault illustrated in the accompanying drawings and described below. It is to be understood that the invention is not limited to the specific form thereof shown and described.

20 Of the accompanying drawings,

Figure 1 is a side elevation partly in section of a vault embodying the invention;

Figure 2 is a section on line 2—2 of Figure 1; and

25 Figure 3 is an enlarged section on line 3—3 of Figure 1.

Referring to the drawings, the numerals 10 and 11 represent the bottom and top respectively of a vault which may be constructed 30 of a plastic material such as concrete suitably reinforced as at 12, 12. Both bottom and top are lined with sheet metal which preferably is non-corrodible, for example, copper, the lining, which is indicated at 13^a and 13^b respectively on the bottom and top, being interlocked with the concrete by any of a number of known methods to provide an integral structure.

35 To provide an effective joint between the bottom and the top, the former is formed with a groove 14 about its perimeter, the inner wall of which may be substantially perpendicular and the outer wall of which is inclined 40 toward the outer edge of the bottom, the sheet metal of the lining being folded about the perimeter of the bottom to define the groove, the marginal portions 13^c of the linings 13^a being preferably bent downwardly and inwardly 45 at the outer edges of the bottom and

embedded in the plastic of the bottom during manufacture thereof.

The top 11 is provided with a downwardly extending flange 15 which may constitute the marginal portions of the lining 13^b doubled and bent downwardly about the perimeter of the top and adapted to engage in groove 14 of the bottom in close relation to the inner wall thereof, the flange 15 preferably being perpendicular to cooperate with the inner wall of said groove and to leave a space in the groove all about the joint.

The top and bottom may be so constructed that the top seats on the bottom as at 16 with the flange 15 in the groove 14 and the top is of such dimensions that the top of groove 14 will be left open or exposed when the top is seated on the bottom. This permits of easy and effective sealing of the box which may be accomplished by filling the groove 14 with solder or other suitable sealing metal or material to permanently seal the joint against seepage of water therethrough.

55 It will be apparent from the foregoing that a burial vault has been provided which for all practical purposes will be permanent and indestructible. Obviously modifications of the invention may be resorted to without departing from the spirit of the invention or from the scope of the appended claims.

60 What is claimed is:

1. A burial vault comprising a bottom and top formed of plastic material each provided with a lining of non-corrosive metal, the body being formed with a groove about its perimeter and the marginal portion of the lining for the bottom being formed to provide a lining for said groove and to provide a portion extending about the outer corners of the bottom and downwardly and inwardly into the plastic material forming said bottom, said top being of such dimensions that when applied to the bottom its edges are adjacent the inner wall of said groove, the marginal portion of the lining on the top having a portion forming a downwardly extending flange adapted to extend into said groove adjacent the inner wall thereof whereby when the top is applied to the bottom the groove will be open about the vault, said groove be- 65 70 75 80 85 90 95 100

ing filled with a solder to seal the linings of the vault together.

2. A burial vault comprising a bottom and top formed of plastic material each provided with a lining of non-corrosive metal, the body being formed with a groove about its perimeter and the marginal portion of the lining for the bottom being formed to provide a lining for said groove and to provide 10 a portion extending about the outer corners of the bottom, said top being of such dimensions that when applied to the bottom its edges are adjacent the inner wall of said groove, the marginal portion of the lining 15 on the top having a portion forming a downwardly extending flange adapted to extend into said groove adjacent the inner wall thereof whereby when the top is applied to the bottom the groove will be open about the 20 vault, said groove being filled with a solder to seal the linings of the vault together.

3. A burial vault comprising a bottom and top formed of plastic material each provided with a lining of non-corrosive metal, the 25 body being formed with a groove about its perimeter and the marginal portion of the lining for the bottom being formed to provide a lining for said groove, said top being of such dimensions that when applied to the 30 bottom its edges are adjacent the inner wall of said groove, the marginal portion of the lining on the top having a portion forming a downwardly extending flange adapted to extend into said groove adjacent the inner wall thereof whereby when the top is applied to the bottom the groove will be open about the 35 vault, said groove being filled with a solder to seal the linings of the vault together.
